UNITED STATES PATENT OFFICE.

THOMAS FOX, OF LIVERPOOL, ENGLAND.

GAS METER.

Application filed November 2, 1921. Serial No. 512,293.

To all whom it may concern:

Be it known that I, THOMAS FOX, subject of the King of Great Britain, residing in Liverpool, in the county of Lancaster and 5 Kingdom of England, have invented certain new and useful Improvements in Gas Meters, of which the following is a specification.

This invention relates to dry gas meters. 10 It has been found that owing to the changed conditions of the manufacture of gas, the dry meter often passes large volumes of unregistered gas.

This is attributable mainly to two causes; 15 firstly foreign matter is deposited on the valves and covers, thus allowing unregistered gas to escape to the exhaust. Secondly, the gas acts on the diaphragm and strips the dressing out of the leather. After this 20 stripping has taken place, the leather commences to become porous and hard, and breaks away, and commences to pass unregistered gas, and the leather has had then but a short life, and considerable expense is entailed in overhauling the meters.

According to our invention these defects are overcome in that the valve chamber is adapted to retain a shallow bath of oil, and oil supply means are provided which differ 30 from those previously proposed to supply oil to the diaphragm in that oil is supplied to cover the valves and other working parts with a film and keeps the diaphragm pliable. Constructional features leading to 35 this result will be described hereafter.

The invention is more particularly described with reference to the accompanying drawings in which:—

Fig. 1 is a longitudinal elevation of the 40 meter with the top chamber in section.

Fig. 2 is an end elevation of the meter.

Inside the top 10 of the meter 1 is situated the valve chamber 2 which encloses the valves 3. The valves 3 are of any known 45 type, but it is essential that their seats 4 are raised above the level of the valve plate 5. The gas, entering the meter 1, travels down the side pipe 6 and then along the horizontal pipe 7. The pipe 7 may be situated 50 below the valve plate 5 as shown in Fig. 1, in which case entrance to the valve chamber 2 is afforded by a hole in the valve plate 5.

The pipe 7 may on the contrary run hori-

zontally above the valve plate 5 to the top 55 or bridge 8 of the valve chamber 2 necessitating the provision of a hole in the bridge 8 to allow the gas to enter.

In the former case as shown in the drawings we form around the hole (not shown) 60 in the valve plate 5 a vertical wall of like material the height of which wall above the valve plate 5 exceeds that of the valve seats 4. Fixed to the side of the meter 1 is a metal tube 9 of small cross section and 65 of U form as shown in Figs. 1 and 2 provided at the top with a cap 11 adapted to be sealed to prevent interference and at the bottom with a bent portion 12 entering the valve chamber 2. Prior to use, or when 70 necessary during use, oil is poured down the pipe 9 by which it enters the valve chamber 2 until of such a depth that it reaches half way up to the surface of the raised valve 75 seats 4, thus entirely covering the bottom of the valve chamber 2. Owing to creeping of the oil it covers the valves 3 and valve seats 4 and all working parts and when these latter move, oil is thrown in small quantities 80 down the valve ports on to the diaphragm 85 of leather or like material 13. The oil is prevented from entering the horizontal pipe 7 by the wall which is fixed to the valve plate 5 in any well known manner. The cap 11 is internally threaded to screw on the 90 tube 9 and when the oil has been poured in this cap is sealed. Should the tube not be gas tight at the top end 11, the escape of 95 gas from the valve chamber is prevented by the seal of oil in the U tube 9. When the meter is in use oxidation of the surface due to the action of constituents of the gas is prevented by the film of oil which gradually creeps over the surface of the valve chamber.

While oil has been referred to as the protective liquid it is evident that other liquids possessing like properties might be used instead of oil.

We declare that what we claim is:—

1. The method of protecting exposed parts 100 of a dry type gas meter against the action of the gas, which consists in providing a shallow bath of protective liquid around the valves, at a level below that of the valve seating, so that the liquid is delivered in 105 small quantities to the valves by capillary action and by them directed to the leather diaphragm as a result of the movement of

said valves the oil also creeping over the surface of the valve chamber.

2. In a dry type gas meter means to supply oil to protect working surfaces exposed to the action of the gas, comprising a gas inlet pipe, a valve chamber connected to said inlet pipe and adapted to retain a layer of

oil freely exposed to gas entering said chamber, a pipe to supply oil to said chamber at any time and means to prevent the escape 10 of gas through said supply pipe.

In witness whereof, I have hereunto signed my name this 19th day of October, 1921.

THOMAS FOX.
